COMPRESSED GAS OPERATED CIRCUIT
BREAKER

Hans Thommen and Arnold Amstutz, Baden, Switzerland, assignors to Aktiengesellschaft Brown, Boveri & Cie, Baden, Switzerland, a joint-stock company

Application July 25, 1949, Serial No. 106,686
In Switzerland July 31, 1948

7 Claims. (Cl. 200—148)

1

The present invention relates to circuit breakers of the gas blast type in which the breaker contacts, normally spring loaded into engaging relation in a switch chamber, are separated upon an application of pressure gas to the contacts, and remain open so long as the gas pressure is maintained in the chamber. Closure of the contacts is effected by releasing the gas pressure in the chamber thus permitting the counter force of the contact loading device to move the contacts to closed position.

With switches of the foregoing type, it is most desirable that the contact reclosure action take place as rapidly as possible and also while gas pressure is still present in the switch chamber to prevent formation of long switching-in arcs. Moreover, care must be taken that the contact pressure is great enough to prevent the inherent electrodynamic forces from separating the contacts and also to prevent mechanical rebounding of the contacts. These switching problems are most acute when the breaker is to be switched in without disturbance in cases involving heavy short circuit switching out currents of short duration.

The object of the present invention is to provide an improved construction for effecting a more rapid and positive reclosure of the contacts upon release of the gas pressure from the switch chamber. A more specific object is to provide a reclosing device for circuit breaker contacts in which the contact reclosing force is constituted by the pressure gas itself acting through an auxiliary cylinder and piston in the switch chamber upon release of the gas pressure, and which auxiliary cylinder is charged with the pressure gas upon an opening operation of the circuit breaker contacts.

The foregoing and other objects and advantages inherent in the invention will become more apparent from the following detailed description of a typical embodiment thereof when considered with the accompanying drawing which is a vertical view of the improved switch arrangement with some components shown in central section and others in elevation.

Referring now to the drawing, the switch is seen to be comprised of a hollow insulator column 10 upstanding upon a valve body 11 that is united with a tank 12 containing a compressed gas such as air which is used for actuating the switch contacts. The valve body 11 includes two valve plates 13, 14 cooperative with opposite ends of the valve cylinder 15 and interconnected by rod 16 for operation simultaneously in such man-

2

ner that when valve plate 13 is seated upon the cylinder end 15a, valve plate 14 is removed from its seat on the cylinder end 15b and vice versa. The cylinder 15 contains an opening 15c leading therefrom into the lower end of the insulator column 10 and a vent 15d from cylinder end 15a to atmosphere. Thus when the valve plates 13, 14 occupy the positions shown in the drawing, the interior of the column 10 is placed in communication with the atmosphere through openings 15c and 15d; similarly when the valve plates 13, 14 are shifted to the positions shown in broken lines, vent 15d is cut off by closure of valve cylinder end 15a and compressed air is admitted from tank 12 into the column 10.

At an intermediate point along the column 10 an annular plate 17 of conductive material is inserted. This plate includes a terminal 18 to which one side L of the line is connected, and a 20 spider 19 at the center or hub portion of which is supported a stationary cylindrical contact 20. Cooperative with this contact is a movable tubular contact 21. The lower open end of contact 21 seats upon the end of contact 20, the upper end is secured to a valve plate 22 having a peripheral flange 22a and ports 23 are provided in the tubular wall to permit discharge of the gases formed upon separation of the contacts.

Upstanding upon the insulator column 10 and of about the same internal diameter is another tubular column 24 of conductive material that carries a transversely arranged conductive plate 25 inserted between the ends thereof. Plate 25 includes one or more longitudinal gas passageways 26 therethrough, one or more gas ports 27 leading from the lower face of the plate to atmosphere, and an axial opening 28 that serves as a sleeve for guiding a conductive piston rod 29. The lower end of rod 29 is secured to valve plate 22 and a compression spring 30 carried between the lower face of plate 25 and valve plate 22 is preferably included to urge the interconnected components, i. e. piston rod 29, valve plate 22 and tubular contact 21 downwardly so that contacts 20, 21 are normally loaded by the spring 30 into engagement.

A piston 32 also of conductive material carried at the top of rod 29 works in a conductive cylinder 33 that is enclosed by a housing 34 also of conductive material. The upper end wall of cylinder 33 is provided with a very large opening 35 and a port 36 is provided in the side wall of the cylinder in order to permit compressed gas to flow from the switch chamber 37 into a pressure storage, auxiliary chamber 38 after the piston

32 has moved to the position shown in broken lines.

Upstanding upon housing 34 is a second terminal 39 to which line L₁ is connected and since the components associated with the tubular contact 21 are all conductive, a low resistance path for current flow is thus provided from line L through to the movable contact 21 of the switch.

As stated at the outset of the application, the object of the present invention is to provide a more rapid and positive reclosing action of the switch contacts. The construction described assures the desired result and operates in the following manner:

To effect an opening of the switch contacts 20, 21, valve control rod 16 is shifted by suitable control means (not illustrated) to the right from the position shown in the drawing thus closing end 15a of valve cylinder 15 and open-cylinder end 15b. Compressed air now flows from tank 12 through valve 11 into the main switch chamber 37 causing contact 21 to move upward and away from contact 20 thus breaking the connection between lines L and L₁. The arc formed upon separation of the contacts is bathed on all sides by the compressed gas flowing upward around and through the movable contact 21 and ultimately extinguished, the arc discharge gases flowing out through exhaust port 27 to atmosphere. Valve plate 22 and piston 32 rise simultaneously with the movable contact 21 ultimately reaching the positions shown in broken lines at which time exhaust port 27 is closed by valve plate 22 thus shutting off the main switch chamber 37 from the surrounding air and opening port 36 in cylinder 33 to place the main switch chamber 37 in communication with the auxiliary chamber 38. The latter now fills with pressure gas from the main switch chamber flowing upwardly through the passageway 26 and the contacts 20, 21 will remain in the separated state being well insulated from one another by the compressed gas that fills chamber 37.

When it is desired to close the switch contacts, valve control rod 16 is shifted back to the position shown in full lines thus cutting off the interior of the insulator and conductive columns 10, 24 from the compressed air tank 12 and simultaneously venting the columns to atmosphere through opening 15d. The air under pressure in the columns is now discharged rapidly through opening 15d. The air under pressure in the columns is now discharged rapidly through opening 15d thus dropping rapidly the pressure on the lower side of piston 32 which is then moved rapidly downward forthwith by the gas under pressure stand in the auxiliary chamber 38, and which pressure is applied to the upper side of piston 32 through the top opening 35 in cylinder 33. Piston 32 and therefore the movable contact member 21 are propelled downwardly with great force thus effecting a rapid and positive reclosure of contacts 20, 21 and with such contact pressure that rebounding of the movable contact 21 is made impossible. Spring 30 also exerts a reclosing force on the movable contact 21 but as the spring force constitutes but a very small fraction of the total reclosing force, it can be disregarded. In fact, it is possible to eliminate the spring altogether so that the switching operations are carried out exclusively by pneumatic action.

An inherent and important advantage of the control which has been described is that the de-

sired pneumatic action is always attained irrespective of the magnitude of the air pressure in tank 12. The control operates equally as well on either high or low pressures and is obviously self compensating for different air pressures since the air pressure built up in the auxiliary chamber 38 is not absolute but rather variable with the pressure in the main switch contact chamber 37.

In conclusion, we wish it to be understood that the constructional embodiment of the invention is typical only and hence may be modified by others without however departing from the spirit and scope of the invention as defined in the appended claims.

We claim:

1. A compressed gas circuit breaker comprising, a switch contact chamber, a pair of normally closed switch contacts in said chamber, said contacts being separated by compressed gas upon admission thereof to said chamber and maintained in said separated state by the gas pressure in said chamber, a source of compressed gas, valve means for establishing communication between said chamber and gas source, valve means controlling relief of the gas pressure from said chamber, a pressure storage auxiliary chamber communicable only with said switch contact chamber, a piston cooperative with a movable one of said contacts for effecting reclosure thereof, opposite sides of said piston being continuously exposed respectively to the gas pressures in said switch contact and auxiliary chambers, and means for charging said auxiliary chamber with compressed gas from said switch contact chamber whereby to effect movement of said piston in the contact reclosing direction by the gas pressure in said auxiliary chamber forthwith upon relief of the gas pressure from said switch contact chamber.

2. A compressed gas circuit breaker comprising, a switch contact chamber, a pair of normally closed switch contacts in said chamber, said contacts being separated by compressed gas upon admission thereof to said chamber and maintained in said separated state by the gas pressure in said chamber, a source of compressed gas, valve means for establishing communication between said chamber and gas source, valve means controlling relief of the gas pressure from said chamber, a pressure storage auxiliary chamber, a piston cooperative with a movable one of said contacts for effecting reclosure thereof, opposite sides of said piston being continuously exposed respectively to the gas pressures in said switch contact and auxiliary chambers, and valve means interconnecting said chambers controlled by said piston for charging said auxiliary chamber with compressed gas from said switch contact chamber whereby to effect movement of said piston in the contact reclosing direction by the gas pressure in said auxiliary chamber forthwith upon relief of the gas pressure from said switch contact chamber.

3. A compressed gas circuit breaker comprising, a switch contact chamber, a pair of normally closed switch contacts in said chamber, said contacts being separated by compressed gas upon admission thereof to said chamber and maintained in said separated state by the gas pressure in said chamber, a source of compressed gas, valve means for establishing communication between said chamber and gas source, valve means controlling relief of gas pressure from said chamber, a pressure storage auxiliary chamber,

a piston cooperable with one of said contacts for moving the same in the direction of the other contact to effect reclosure of said contacts, opposite sides of said piston being continuously exposed respectively to the gas pressures in said switch contact and auxiliary chambers, and a passageway between said chambers controlled by said piston for charging said auxiliary chamber with compressed gas from said switch contact chamber whereby to effect movement of said piston in the contact reclosing direction by the gas pressure in said auxiliary chamber forthwith upon relief of the gas pressure from said switch contact chamber.

4. A compressed gas circuit breaker as defined in claim 3 wherein said piston is secured to one of said contacts.

5. A compressed gas circuit breaker as defined in claim 3 wherein said auxiliary chamber includes an open cylinder within which said piston slides, and the said passageway between said chambers is constituted by an opening through the cylinder wall.

6. A compressed gas circuit breaker comprising, a switch contact chamber, a pair of normally closed switch contacts in said chamber, said contacts being separated by compressed gas upon admission thereof to said chamber and maintained in said separated state by the gas pressure in said chamber, a source of compressed gas, valve means for establishing communication between said chamber and gas source, valve means controlling relief of gas pressure from said chamber, a pressure storage auxiliary chamber, a piston secured to one of said contacts for moving the same in the direction of the other contact to effect reclosure of said contacts, opposite sides of said piston being continuously ex-

25

30

35

posed respectively to the gas pressures in said switch contact and auxiliary chambers, spring means cooperable with the contact to which said piston is secured for loading said contact in the contact reclosing direction, and a passageway between said chambers controlled by said piston and opened upon separation of said contacts for charging said auxiliary chamber with compressed gas from said switch contact chamber whereby to effect movement of said piston in the contact reclosing direction by the gas pressure in said auxiliary chamber and said spring forthwith upon relief of the gas pressure from said switch contact chamber and in a counter direction by the compressed gas when admitted to said switch contact chamber.

7. A compressed gas circuit breaker as defined in claim 6 and which further includes a port in said switch contact chamber for venting arc discharge gases due to contact separation, and valve means controlled by the movable one of said contacts for closing said port subsequent to separation of the contacts.
